[57] CLAIM

The ornamental design for an inflatable, reflective solar oven, as shown and described.

DESCRIPTION

FIG. 1 is a front elevational view of an inflatable, reflective solar oven showing our new design, the rear being a mirror image;

FIG. 2 is a perspective view thereof;

FIG. 3 is a cross-sectional view thereof taken along line 3—3 of FIG. 2.

The opaque surface is reflective, and the oblique lines represent a transparent surface.
